COIL CLEANER

William M. Marker, Los Angeles, Calif.

Application September 19, 1934, Serial No. 744,678

13 Claims. (Cl. 225—12)

This invention relates to a coil cleaner and relates more particularly to a device for cleaning beer coils, etc. A general object of the invention is to provide a simple, practical and inexpensive device for removing accumulations of slime, etc., from coils and pipe lines handling beer.

The pipes and coils of apparatus for handling and dispensing beer must be cleaned at short intervals to remove undesirable accumulations. Heretofore it has been the usual practice to clean beer coils and beer handling piping systems with chemicals or steam, or both. These methods are not altogether satisfactory as they are injurious to the coils, pipes, fittings and valves and often put the apparatus out of service for substantial periods, particularly where the coils or lines extend through refrigerators or cooling apparatus. The interiors of coils and pipes passing beer become coated with a relatively hard thin incrustation called beer stone, which is very desirable as it prevents direct contact of the beer with the metal of the coils and pipes. The steam and chemicals heretofore employed in cleaning the coils and pipes, injured and often destroyed the beer stone with the result that the beer later passed through the coils and pipes is given a metallic flavor or taint.

Another object of the present invention is to provide a practical, effective device for cleaning coils and pipes for handling beer that removes the undesirable accumulations from the coils and pipes without injuring the beer stone or the fittings and valve of the apparatus.

Another object of the invention is to provide a device for quickly removing slime and undesirable accumulations from coils and pipes carrying beer that does not necessitate the removal of the coils or pipes and requires that the apparatus be out of service for a minimum period.

Another object of the invention is to provide a device of the character mentioned that passes or circulates a cleansing or scouring material through the coil and/or pipes which does not taint the apparatus.

Another object of the invention is to provide a device of the character mentioned that may be operated by water under pressure from a city water supply pipe or the like.

Another object of the invention is to provide a coil cleaner of the character mentioned that is small and compact and easy and convenient to use in restricted or confined situations.

Another object of the invention is to provide a device of the character mentioned in which the

effect of the cleansing process or action may be observed when the device is in operation.

A further object of the invention is to provide a coil cleaner of the character mentioned that embodies a minimum number of simple, inexpensive parts and comprises a single upright body having a relatively small diameter.

The various objects and features of the invention will be fully understood from the following detailed description of a typical form and application of my invention, throughout which reference is made to the accompanying drawings, in which:

Fig. 1 is a front elevation of the device provided by the present invention showing it connected with a coil. Fig. 2 is an enlarged horizontal detailed sectional view taken as indicated by line 2—2 on Fig. 1. Fig. 3 is an enlarged vertical detailed sectional view taken as indicated by line 3—3 on Fig. 1. Fig. 4 is an enlarged transverse or horizontal detailed sectional view taken as indicated by line 4—4 on Fig. 3, and Fig. 5 is an enlarged fragmentary vertical detailed sectional view taken as indicated by line 5—5 on Fig. 3.

The coil and pipe cleaning device of the present invention includes, generally, a body 10 having two chambers A and B adapted to be placed in communication with the opposite ends of a coil or piping system, cleansing or scouring material 11 adapted to be circulated from one chamber to the other through the coil or system, and means 12 for reversing the flow of the flushing water and scouring material through the coil or system and the chambers A and B.

The device of the present invention is portable so that it may be readily applied to or connected with beer coils and beer handling systems of various characters. It is a feature of the invention that the body 10 is a single compact upright or vertical unit having a relatively small diameter. The body 10 includes a suitable base 13 for carrying or supporting the various other parts of the device. The base 13 may be round in horizontal cross section and may have a relieved or hollow lower side. The body 10 is sectional including a lower section 14 providing the chamber A, a ported partition or block 15 and an upper section 16 providing the chamber B. The body sections 14 and 16 are formed of glass or other transparent material whereby the operation of the device may be observed. The upper and lower body sections 16 and 14 are preferably cylindrical tubular members as illustrated throughout the drawings. The lower chamber section 14 rests

25

35

40

45

50

55

or seats on the upper side of the base 13 to project upwardly from its center. The partition or block 15 houses or carries the reversing valve means 12 and is provided with the 5 inlet and drain ports as will be subsequently described. In the preferred construction illustrated in the drawings the block 15 is a substantially rectangular member interposed between the upper and lower chamber sections 14 and 16. The 10 flat lower side of the block 15 is seated on the upper end of the section 14. Suitable sealing gaskets 17 may be arranged between the lower end of the section 14 and the base 13 and the block 15 and the upper end of the section 14. The 15 upper chamber section 16 seats on the upper end of the block 15 to project upwardly therefrom in longitudinal alignment with the lower section 14. A plate or head 18 covers the upper end of the section 16. Gaskets 19 are arranged 20 between the ends of the section 16 and the block 15 and the head 18.

Means is provided for holding the several body sections and parts properly assembled. Spaced rods 20 project upwardly from the base 13 and 25 extend through openings in the block 15 and head 18. In the particular case illustrated in the drawings there are four equally spaced rods 20 passing through openings in the corner portions of the block 15 and head 18. The lower portions 30 of the rods 20 extend through openings in downwardly projecting bosses 21 on the hollowed lower side of the base 13. Nuts 22 are threaded on the opposite end portions of the rods 20 to clamp the sectional body structure together.

35 In accordance with the invention the lower portions of the chambers A and B are adapted to be placed in communication with the opposite ends of the coil or piping system to be cleaned. A lateral horizontal port 23 is provided in the base 40 13 and has its inner end in communication with the lower end of the chamber A. The mouth or inner end portion 24 of the port 23 is preferably enlarged to be of substantially the same diameter as the chamber A. A projecting threaded boss 25 is provided on the base 13 at the outer end of the port 23 to receive the end of a hose, nipple, pipe, or coil and to facilitate the connection of the device with the coil or system to be cleaned. A port 26 is provided in the block 15 to communicate with the lower end of the upper body chamber B. The port 26 is enlarged where it joins or has communication with the chamber B. The port 26 extends outwardly through a projecting boss 27 on the block 15. The boss 27 50 may project in the same direction as the boss 25 and may be threaded to facilitate the connection of the device with the coil or system to be cleaned.

60 The cleansing or scouring material 11 is provided in the device to be circulated or forced through the coil or piping system for the purpose of removing the slime and undesirable accumulations. In accordance with the broader aspects of the invention cleansing or scouring 65 materials of various characters may be employed in the device. In cleaning beer coils, where it is desirable to preserve the beer stone, it has been found practical to employ relatively fine rounded gravel or glass beads as the scouring medium or 70 material. In practice the material 11 is initially provided in one chamber, say the chamber A, and is circulated through the coil or piping into the upper chamber B. The means 12 may then be adjusted or set to reverse the flow through the 75 device and piping or coil so that the material 11

is circulated back through the coil or system to the lower chamber A. The material 11 is driven or forced through the piping or coil by water under pressure and together with the water scours and washes all the undesirable accumulations from the system or coil. A valve 28 may be provided to control the port 23 and to prevent the loss of the material 11 from the chamber A when the device is moved from place to place. The valve 28 may be in the form of a tapered plug fitting a correspondingly shaped opening 29 in the base 13. The valve 28 has a transverse opening or port 30 adapted to be moved into and out of registration with the port 23. An operating handle 31 is provided on the projecting end portion of the valve 28. When the valve 28 is in its closed position the cleansing or scouring material 11 which may be in the chamber A cannot spill or pass outwardly through the port 23.

20 The means 12 is provided to control the flow through the device and the coil or piping system and is adapted to be set or adjusted to first pass the water and scouring material 11 from one of the chambers A or B through the coil or system to the other chamber and then may be adjusted or reversed to reverse the flow so that the scouring material 11 is forced or carried through the system or coil to be returned to the first named chamber. The flow controlling means 12 provides or includes a system of ports 30 in the block 15. An inlet port 32 enters the block 15 through a projecting boss 33 which is adapted to be connected with a suitable source S of water under pressure. A drain or outlet port 34 is provided in the block 15 and extends 35 through a projecting boss 35 which is adapted to be connected with a drain pipe 36. The bosses 33 and 35 project from opposite sides of the block 15 and the ports 32 and 34 are in longitudinal and horizontal alignment. A port 37 is 40 provided in the lower portion of the block 15 to communicate with the upper end of the chamber A. A similar port 38 is provided in the upper portion of the block 15 to communicate with the chamber B. The ports 37 and 38 are in 45 vertical alignment.

50 A boss 39 is provided on the block 15 around the upper end of the port 38 to receive the lower end of a pipe 40 which extends upwardly to the upper end portion of the chamber B. A plate or web 41 is attached to the under side of the head 18 and carries a screen 42. The under or lower side of the head 18 is provided with a socket 43 and the screen 42 extends across the lower end of the socket to prevent the passage of the scouring material 11 into the socket from the chamber B. Means is provided for preventing the cleansing or scouring material 11 from entering the port 37 from the chamber A. A socket 44 is provided in the lower side of the 60 block 15 to communicate with the port 37. A perforated plate 45 is arranged across the lower end of the socket 44 and carries a screen 46. The screen 46 prevents the granular scouring material 11 from passing upwardly from the 65 chamber A to the port 37.

70 The inlet port 32, the outlet port 34, and the ports 37 and 38 converge to join or communicate with a horizontal opening 47 in the block 15. The ports 37 and 38 extending to the chambers A and B are spaced 180° apart and the inlet and outlet ports 32 and 34 are spaced between the ports 37 and 38 so that the several ports communicating with the opening 37 are 75 spaced 90° from one another. This relationship

of the ports is clearly illustrated in Fig. 5 of the drawings.

The means 12 includes a valve 48 for controlling the flow through the ports 32, 34, 37 and 38 in the block 15. The valve 48 is in the form of a directional valve turnable or rotatable in the opening 47. The opening 47 may be longitudinally tapered and the valve 48 may be likewise shaped to effectively operate in the opening. The valve 48 has diametrically opposite openings or ports 49 and 50 for connecting the chamber ports 37 and 38 with the inlet and outlet ports. The valve 48 is movable between a position where the port 49 connects the inlet port 32 with the port 37 and the port 50 connects the port 38 with the outlet port 34 and a position where the port 50 connects the inlet port 32 with the chamber port 38 and the port 49 connects the chamber port 37 with the outlet port 34. A stem 51 is provided on the valve 48 and extends outwardly through an annular projection 52 on the block 15. A suitable operating lever or handle 53 is provided on the stem 51. A plug 55 is threaded into the annular enlargement 52 and a spring 54 is arranged under compression between the valve 48 and the plug to act on or urge the valve into the opening 47. Suitable washers 56 may be provided at the opposite ends of the spring 54.

In employing the device of the present invention the bosses 25 and 27 are connected with the opposite ends of a piping system or coil to put the ports 23 and 26 in communication with the ends of the system or coil. In the drawings I have illustrated one branch or end portion 58 of a coil C connected with the boss 25 to communicate with the port 23 and the other end portion 59 of the coil connected with the boss 27 to communicate with the port 26. The water line or source S of water under pressure is connected with the boss 33 to discharge into the port 32 while a suitable drain 36 is connected with the boss 35 to receive the discharging water from the port 34. The granular scouring material 11 may initially be in the lower body chamber A as illustrated in Figs. 1 and 3 of the drawings. The valve 28 is preferably maintained in its closed position during the handling and attachment of the device with the system or coil to prevent the loss of the material 11 from the body chamber. When the system or coil C is to be cleaned the valve 28 is opened and the directional valve 48 is set in the position illustrated throughout the drawings where the inlet port 32 is in communication with the chamber A and the port 38 from the chamber B is in communication with the outlet port 34. Water under suitable pressure is passed through the source or pipe S to flow through the port 32 and ports 49 and 37 into the upper end of the chamber A. This water under pressure passing downwardly through the chamber A carries the scouring material 11 into the system or coil C. The flowing water under pressure carries or forces the granular scouring material 11 through the coil C so that it is effective in removing the undesirable accumulations from the interior of the coil. In practice the material 11 cleans or scours away the relatively soft slime, etc., without removing the beer stone and without injuring the coil and other fittings. The water and material passes from the coil C into the port 26 and then into the upper body chamber B. The water or liquid is free to pass outwardly through the screen 42 and socket 43 into the pipe 40 while

the screen operates to trap the granular scouring material 11 in the chamber B. The loosened slime, being made up of very fine particles, readily passes through the screen and, together with the water, passes down the pipe 40 outwardly through the ports 38 and 50 into the drain 34. As the body sections 14 and 16 are of transparent material the action or operation of the device may be observed. The water or cleaning medium is preferably passed through the device and coil C until the water flowing through the chamber B is clear or substantially clear.

In most instances it is desirable to circulate or pass the granular scouring material 11 through the system or coil several times in both directions to insure a thorough cleansing or removal of undesirable accumulations. To reverse the flow through the device and coil C the valve 48 is turned for approximately 90° so that its ports put the inlet port 32 into communication with the port 38 and put the port 37 from the lower body chamber into communication with the drain port 34. The incoming water under pressure from the port 32 then passes upwardly through the pipe 40 to discharge into the upper portion of the body chamber B. The scouring material 11 that has been trapped in the chamber B is then forced outwardly through the port 26 with the flowing water under pressure to pass or circulate through the coil C. From the coil C the water and material 11 passes through the port 23 into the lower body chamber A. The liquid medium or water and the loosened slime freely passes outwardly through the screen 46 into the socket 44 and ports 37 and 34. The granular scouring material 11 is trapped or retained in the body chamber A as it cannot pass through the screen 46. In the operation of the device it will be observed that the scouring material will leave the chamber in which it is contained in substantially a mass. The scouring material after passing through the coil C will return to the other chamber in substantially a mass followed by a flow of cloudy water, this cloudiness being due to the loosened slime. The water is permitted to circulate through the coil C until the cloudiness disappears indicating the removal of the loosened slime. Upon several reverses of flow no further cloudiness can be developed by the passage of the securing material. This indicates that the undesirable accumulations have been removed from the system or coil C. The supply of water from the pipe S may then be cut off and the device detached from the coil C.

The present invention provides a device for cleaning beer coils and beer handling piping systems that is small and compact and easy to attach and operate. The device is in the form of a single vertically disposed unit that may be readily installed and operated in relatively confined places. The device includes a minimum number of simple, inexpensive parts and is particularly easy to connect to the coil or piping system.

Having described only a typical preferred form and application of my invention, I do not wish to be limited or restricted to the specific form and application herein set forth, but wish to reserve to myself any modifications or variations that may appear to those skilled in the art or fall within the scope of the following claims.

Having described my invention, I claim:

1. A device for cleaning a fluid handling coil or the like including a body having a lower chamber, an upper chamber and a port communicating with the lower chamber and adapted to communicate with one end of the coil, and a partition be-

70
65
75

- 5 between the chambers having a port communicating with the upper chamber and adapted to be put in communication with the other end of the coil, the partition having an outlet port and an inlet port adapted to be connected with a source of fluid under pressure, and reversible means for putting one chamber in communication with the inlet port and the other chamber in communication with the outlet port.
- 10 2. A device for cleaning a fluid handling pipe system including two vertically aligned sections each having a chamber, a partition between the sections having an inlet port to connect with a source of fluid under pressure, an outlet port, and a port for putting one chamber in communication with one end of the system, means for putting the other chamber in communication with the other end of the system, and reversible means carried by the partition for putting one chamber in communication with the inlet port and one chamber in communication with the outlet port.
- 15 3. A device for cleaning a fluid handling pipe system including two vertically aligned transparent sections each having a chamber, a partition between the sections having an inlet port to connect with a source of fluid under pressure, an outlet port, and a port for putting one chamber in communication with one end of the system, means for putting the other chamber in communication with the other end of the system, and reversible means for putting one chamber in communication with the inlet port and one chamber in communication with the outlet port.
- 20 4. A device for cleaning a fluid handling pipe system including two vertically aligned sections each having a chamber, and a partition between the sections having an inlet port to connect with a source of fluid under pressure, an outlet port, and a port for putting one chamber in communication with one end of the system, means for putting the other chamber in communication with the other end of the system, and reversible means for putting one chamber in communication with the inlet port and one chamber in communication with the outlet port, the reversible means including a directional valve in the partition.
- 25 5. A device for cleaning a fluid handling pipe system including two vertically aligned sections each having a chamber, and a partition between the sections having an inlet port to connect with a source of fluid under pressure, an outlet port, and a port for putting one chamber in communication with one end of the system, means for putting the other chamber in communication with the other end of the system, and reversible means for putting one chamber in communication with the inlet port and one chamber in communication with the outlet port, granular material in one chamber adapted to be circulated through the system, and reversible means for putting one chamber in communication with the inlet port and one chamber in communication with the outlet port.
- 30 6. A device for cleaning a fluid handling pipe system including two vertically aligned sections each having a chamber, and a partition between the sections having an inlet port to connect with a source of fluid under pressure, an outlet port, and a port for putting one chamber in communication with one end of the system, means for putting the other chamber in communication with the other end of the system, granular material in one chamber adapted to be circulated through the system, means for preventing passage of said material from the chambers to the outlet port, and reversible means for putting one chamber in communication with the inlet port

and one chamber in communication with the outlet port.

7. A device for cleaning a fluid handling pipe system including a base, a section on the base having a chamber, a block arranged on the section and having an outlet port and an inlet port to be connected with a source of fluid under pressure, a second section extending from the block having a chamber, the base having a port communicating with the chamber of the first mentioned section and adapted to be placed in communication with one end of the pipe system, the block having a port communicating with the chamber of the second section and adapted to be placed in communication with the other end of the pipe system, and valve means carried by the block for putting one chamber in communication with the inlet port and the other chamber in communication with the outlet port.

8. A device for cleaning a fluid handling pipe system including a base, two tubular transparent sections, one section projecting upwardly from the base, a block supported on the upper end of said section, the other section being supported on the block to project upwardly therefrom, the base having a port communicating with the interior of the lower section and adapted to be connected with one end of the pipe system, the block having an outlet port, an inlet port to be connected with a source of fluid under pressure, and a port communicating with the interior of the upper section and adapted to be connected with the other end of the pipe system, granular material to be circulated through the pipe system from one chamber to the other, and a reversible valve in the block for putting the inlet port in communication with the interior of one section and the outlet port in communication with the interior of the other section.

9. A device for cleaning a fluid handling pipe system including a base, a section on the base having a chamber, a block arranged on the section and having an outlet port and an inlet port to be connected with a source of fluid under pressure, a second section extending upwardly from the block having a chamber, the base having a port communicating with the chamber of the first mentioned section and adapted to be placed in communication with one end of the pipe system, the block having a port communicating with the chamber of the second section and adapted to be placed in communication with the other end of the pipe system, and having ports communicating with the two chambers, a reversible valve for putting one of the last named ports in communication with the inlet port and the other of the last named ports in communication with the outlet port, granular material to be circulated through the pipe system from one chamber to the other, and screens preventing the passage of said material into said last named ports.

10. A device for cleaning a fluid handling pipe system including two vertically spaced chambers each having a port, said ports being adapted to be connected with the opposite ends of the pipe system, a partition between the chambers having an inlet port, an outlet port, a port in communication with the lower chamber, and a fourth port, a pipe extending from the fourth port to the upper portion of the upper chamber, a reversible valve for connecting one of the last named ports with the inlet port and the other with the outlet port, and granular material for

circulation through the pipe system from one chamber to the other.

5 11. A device for cleaning a fluid handling pipe system including two vertically spaced chambers each having a port, said ports being adapted to be connected with the opposite ends of the pipe system, a partition between the chambers having an inlet port, an outlet port, a port in communication with the lower chamber, and a fourth

10 port, a pipe extending from the fourth port to the upper portion of the upper chamber, a reversible valve for connecting one of the last named ports with the inlet port and the other with the outlet port, granular material for circulation 15 through the pipe system from one chamber to the other, and screen for preventing the passage of said material through the said pipe and the port in the partition communicating with the lower chamber.

20 12. A device for cleaning a fluid handling pipe system including a base, a section on the base having a chamber, a block arranged on the section and having an outlet port and an inlet port to be connected with a source of fluid under pressure, a second section extending upwardly from the block having a chamber, the base having a port communicating with the chamber of the first mentioned section and adapted to be placed

in communication with one end of the pipe system, a valve for controlling the port in the base, the block having a port communicating with the chamber of the second section and adapted to be placed in communication with the other end of the pipe system, and valve means carried by the block for putting one chamber in communication with the inlet port and the other chamber in communication with the outlet port.

10 13. A device for cleaning a pipe system including a base, a section on the base having a chamber, a partition at the upper end of the section, a second section arranged on the partition to extend upwardly therefrom, the partition having an inlet port, an outlet port, a third port communicating with the lower chamber and a fourth port, a cap closing the upper end of the upper chamber and having an opening in communication therewith, a pipe extending through the upper chamber and connecting the opening with the fourth port, means for putting the chambers in communication with the opposite ends of the pipe system, and a reversible valve in the partition controlling the said third and fourth ports and operable to connect one with the inlet port 20 and the other with the outlet port.
